(57) **CLAIM**

The ornamental design for an operator cabin mirror assembly for work vehicle, as shown and described.

DESCRIPTION

FIG. 1 is a rear, left isometric view of an operator cabin mirror assembly for work vehicle according to our new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, right perspective view of an operator cabin mirror assembly for work vehicle according to another embodiment of our new design, the various views thereof being mirror images of FIGS. 2-7.

The evenly dashed lines depict portions of the operator cabin mirror assembly for work vehicle that form no part of the claimed design. The unevenly dashed lines indicate that the appearance of any portion of the article between the break lines forms no part of the claimed design. The brackets in FIGS. 1, 2 and 5-8 indicate that the article includes features shown at opposite sides of the break lines and otherwise form no part of the claimed design.
